UNITED STATES PATENT OFFICE.

MILTON TIBBETTS, OF DETROIT, MICHIGAN, ASSIGNEE TO PACKARD MOTOR CAR COMPANY, OF DETROIT, MICHIGAN, A CORPORATION OF MICHIGAN.

HYDROCARBON-MOTOR.

1,111,773.

Specification of Letters Patent. Patented Sept. 29, 1914.

Application filed June 16, 1913. Serial No. 567,236.

To all whom it may concern:

Be it known that I, MILTON TIBBETTS, a citizen of the United States, and resident of Detroit, county of Wayne, State of Michigan, have invented certain new and useful Improvements in Hydrocarbon-Motors, of which the following is a specification.

This invention relates to hydrocarbon engines or motors, and particularly to engines of the sliding valve type.

One of the objects of this invention is to provide a starting system whereby the engine may be started without the necessity of cranking.

Another object is to provide a novel compression relief.

Further objects will appear from the detail description, taken in connection with the accompanying drawings, in which—

Figure 1 is a longitudinal section and part elevation of a four-cylinder motor embodying some of the features of my invention; Fig. 2 is a cross section approximately on the line 2—2 of Fig. 1; Fig. 3 is a fragmentary view similar to Fig. 2 with the moving parts in different relative positions; Fig. 4 is a fragmentary section on the line 4—4, Fig. 2, showing the piston at the upper dead center of the compression stroke; Fig. 5 is a plan view of a multicylinder motor showing the starting arrangement; Fig. 6 is a diagram showing the operation and positions of the starting ports; Fig. 7 is an elevation of a multicylinder engine showing in section another form of starting arrangement; Fig. 8 is an enlarged section of the parts shown in Fig. 7; and Fig. 9 is a vertical section through an engine cylinder, showing compression relief ports.

Referring to the drawings, 1, 2, 3 and 4 represent respectively the four cylinders of the multicylinder motor shown in Fig. 1, and 5 represents the crank shaft turning in the bearings 7, in the crank case 6. As shown particularly in Fig. 2 this crank case is preferably made in three parts, viz. the upper part or supporting frame 8, the intermediate section 9 between which and the support 8 the bearings 7 are contained, and the bottom cover or oil well section 10 which latter section is easily removable to give access to the interior of the crank case. The cranks 11 of the crank shaft 5 are set 180° apart and the connections are so made that

the order of firing when the motor is operated on the four-stroke cycle, is successively in cylinders 1—2—4—3.

The fly wheel is shown at 12 mounted on crank shaft 5. In each of the cylinders is arranged the usual piston 13 connected to its respective crank by the connecting rod 14. Each cylinder is provided with a suitable inlet port 15 and an opposite outlet or exhaust port 16, these ports having suitable pipe connections with the carburetor and exhaust pipe respectively. Each cylinder also has a removable head 17, the central portion 19 of which extends down into the cylinder coaxially with the piston, leaving an annular space between its periphery and the cylinder walls above the inlet and exhaust ports. The cylinders and their heads are suitably water-jacketed as shown at 18.

Arranged to reciprocate longitudinally in each cylinder are two concentric sleeves 75 which surround the piston and the downwardly extending central portion of the head above described, the inner sleeve forming the piston barrel and both sleeves having ports arranged to coöperate to open the inlet 80 and exhaust ports of the cylinder. The inner sleeve 23 has the oppositely arranged ports 24, 25 which during the movement of the sleeve register respectively with the ports 15 and 16 and the outer sleeve 26 has the 85 ports 27 and 28 which also register at times with the ports 15 and 16 respectively. From this it will be observed that in order to open communication between the inlet port 15 and the interior of the cylinder it is necessary that the ports 24 and 27 shall simultaneously register with the inlet port 15, and in order to open communication between the interior of the cylinder and the exhaust, ports 25 and 28 shall simultaneously register 90 with said exhaust port 16. It will also be observed upon reference to the drawings that the above mentioned parts are so arranged and the sleeves so reciprocated that the inlet port 15 is open to the interior of the 100 cylinder during every other down stroke of the piston, or one opening for every two complete revolutions of the crank shaft, and the same is true of the exhaust port 16 except that it is opened on the upstroke of the piston which succeeds the firing down stroke thereof. The mechanism for thus reciprocating the sleeves will now be described.

2

Mounted preferably in the upper or supporting section 8 of the crank case is a valve operating shaft 29, shown in Fig. 1 as turning in the bearings 30. This shaft may 5 be rotated by the crank shaft at half the speed of said crank shaft, by any suitable gearing which gives it one revolution for every two revolutions of the crank shaft. In the present instance this gearing includes 10 the sprocket 31 on the shaft 29 and the sprocket 32 on the crank shaft, the former sprocket having twice as many teeth as the latter, and a chain 33 operatively connects the sprockets. A forward extension 34 on 15 the supporting section of the crank case forms a housing for the sprockets and chain, and the front end of this housing is closed by a removable cover 35 as will be clearly understood.

20 The valves of the separate cylinders are operated successively by means of eccentrics on the valve shaft through connecting rods 37. The method of actuating the eight sleeves from six eccentrics is illustrated in 25 Figs. 1 and 2 of the drawings and by referring thereto it will be seen that the eccentric 36 reciprocates the inner sleeve 23 of cylinder No. 1 through the connecting rod 37 which extends between said eccentric 36 30 and the ears 38 on the enlarged lower end 39 of said sleeve 23, the pin 40 passing through the upper end of said connecting rod 37 and the ears 38 as will be readily understood. The eccentric 41 reciprocates 35 the outer sleeve 26 of cylinder No. 1 and the inner sleeve 23 of cylinder No. 2 through the connecting rod 37. The eccentric 42 reciprocates the outer sleeve 26 of cylinder No. 2 through its connecting rod 37. Thus 40 the four sleeves of cylinders 1 and 2 are actuated by the three eccentrics 36, 41 and 42, this being rendered possible by the fact that the outer sleeve 26 of cylinder No. 1 and the inner sleeve 23 of cylinder No. 2 45 move coincidentally. Also it will be noticed that the ears 38 on the outer sleeves of cylinders 1 and 2 are dropped down slightly below the lower edge of the sleeves, and this is necessary in the case of the outer sleeve 50 of cylinder No. 1 to provide for its connection with the connecting rod 37 by the same pin 40 that connects said rod with the inner sleeve 23 of cylinder No. 2. In the case of cylinder No. 2 it is desirable since it makes 55 it possible to have all of the connecting rods 37 of the same length, which of course is a distinct advantage in manufacturing.

The arrangement of the eccentrics and sleeves of cylinders 3 and 4 is identical with 60 that of cylinders 1 and 2 except that the parts are shown in opposite phase with cylinder No. 4 leading. Thus the outer sleeve 26 of cylinder No. 3 is reciprocated through its connecting rod 37 by the eccentric 43; 65 the inner sleeve of cylinder No. 3 and the

outer sleeve of cylinder No. 4 operate coincidentally and are reciprocated through connecting rod 37 by the eccentric 44, and the inner sleeve of cylinder No. 4 is reciprocated through its connecting rod 37 by the eccentric 45. The first, third, fourth, and sixth connecting rods 37 are shown in their extreme up or down position and the second and fifth rods are in intermediate position, while the arrows on them indicate the direction in which they are traveling. 75

Nearly all hydrocarbon motors used in motor vehicle construction at the present time are designed to be started by hand, that is, the first turn of the crank shaft is given by the operator to start the motor on its proper cycle of operation. In the larger motors of this character, some difficulty is experienced in compressing the charge by thus turning the crank shaft by hand and 80 various devices have heretofore been designed for partially relieving the compression stroke of the piston. In a four-stroke cycle motor it is of course desirable that the cylinder be open to the atmosphere to relieve the pressure during a part of the compression stroke of the piston and not during the entire period of this stroke even in cranking, and during all of the other strokes of the piston it should be closed. If a pet 85 cock is employed in the head of the cylinder for the purpose of relieving the compression, this pet cock must also remain open during the intake of the motor and thus considerable air is drawn into the cylinder 90 which rarefies the mixture and increases the difficulty of starting. Moreover, the compression is too much relieved for the reason that the pet cock remains open during the entire compression stroke. The ideal situation 95 therefore is the provision of a separate valve which shall be opened during a part only of the compression stroke of the piston, and in the present invention such a device is embodied, which device will now be described. 100

Referring particularly to Figs. 1 and 2, it will be noted that the inner sleeve 23 is provided in one side with a port 46 and that the outer sleeve 26 has a similar port 115 47, and these ports are so arranged that they will overlap or be in register during a part of the compression stroke of the piston. They are shown so in register in Fig. 3. In the side of the cylinder and adapted to register with the ports 46 and 47, when they themselves are in register, is a relief port 48, the outlet of which is controlled by a pet cock 49, and when said pet cock is opened, the gas discharged from the same 120 enters the pipe 50 by which it is conveyed to the atmosphere beneath the motor or to any other convenient place. 125

The somewhat diagrammatic illustration given in Fig. 3 shows the piston 13 on its 130

compression stroke before it reaches the port 46. Both sleeves are traveling upwardly as is indicated by their connections with the eccentrics and by the arrows, and as the outer sleeve will from that point travel slightly faster than the inner sleeve, owing to the greater angularity of its connecting rod 37, it will be seen that the ports 46, 47 and 48 will be out of register at about the same moment that the piston 13 overrides the port 46. Thus the relief port 48 is cut off from the interior of the cylinder until the next compression stroke of the piston, the ports 46 and 47 being out of register on the next up or exhaust stroke of the piston. Of course, the pet cock 49 may be operated to close the port 48 at any time and the compression relief is then inoperative.

Figs. 1, 2, 4 and 5 show an arrangement whereby the engine may be started automatically. The inner sleeve 23 has formed therein a port 51 and the outer sleeve has formed therein a port 52. A port 53 is formed in the cylinder wall and connects with a pipe or conduit 54. In this particular embodiment the invention is shown as applied to a four-cylinder engine, though it may be applied to single cylinder engines as well. The pipes 54 of the outside cylinders are connected to a pipe or conduit 58 while the inside cylinder ports 53 are connected to a T 56 which is connected to 58 by means of a pipe 57. The pipe or conduit 58 is connected to a motive fluid storage tank 60 by means of a pipe 59 and a suitable cut-off valve 61 is located in this pipe 59. The pipes 55 and 57 are provided with valves 62 so that the connections between the ports 53 and the pipe 58 may be cut off. These valves 40 may be of the same construction as valves 49, and each valve is preferably provided with an arm which engages a single shifting rod 63 provided with a handle 64. By means of this construction all of the valves 62 may be opened and closed simultaneously by operating the handle 64. The valves 49 may also be connected by means of a shifting rod 65 provided with a handle 66.

The diagram in Fig. 6 shows the relative positions of the cylinder port 53 and the sleeve ports 51 and 52. In this diagram, 70 designates the bottom of the cylinder head and the ports in the cylinder and sleeves are designated by the same reference characters as in Fig. 4. The line 71 represents the period where the piston is on the upper dead center at the end of the compression stroke, line 72 represents the period where the exhaust opens, line 73 represents the period where the piston is on the next lower dead center, line 74 represents the period where the piston is on the upper dead center of the exhaust stroke and line 75 represents the period where the piston is on the next lower dead center. The line 76 represents the

travel of the piston and lines 77 and 78 represent the travel of the ports in the valve sleeves, the travel of the ports in the valve sleeves being shown on an exaggerated scale with respect to the travel of the piston.

70

Referring to Fig. 4, the piston is shown on the upper dead center at the end of the compression stroke and is ready to start downwardly. As the piston starts downwardly the valve sleeves will be operated to open communication between the port 53 and the cylinder, the directions of the valve sleeves being indicated by arrows. Ordinarily the piston will not stop on dead center, and therefore the port 53 will be slightly opened. If now the valves 61 and 62 are opened and the tank 60 contains a gas, as air, under pressure, this gas will flow into the cylinder and move the piston downwardly. The shaded portion of Fig. 6 shows the period when the ports 51 and 52 are in communication, and it will be noted that the port 53 is not closed until just before the exhaust port is opened. The pressure is thus applied to the piston for nearly a full stroke. The piston and crank shaft will now be operated under the impulse of the fly-wheel so as to exhaust the gases, and during the next forward stroke of the piston the combustible gases are drawn in and compressed during the succeeding stroke and ignited. If the pressure of the gas is not sufficient to bring about this operation the relief arrangement may be used in connection with this starting arrangement so that the compression will be relieved until the engine has started up. After the engine has started up the valves 49 and 62 are closed. It will be noted that when the ports 51 and 52 are in alignment during the exhaust and suction strokes that they are out of alignment with the port 53. This is clearly shown in Fig. 6.

120

125

130

Referring to Figs. 7 and 8, which show another form of motor and in which the section shown in Figs. 7 and 8 is taken at an angle of 45° to a center line running along the cylinders; the cylinder, the valve sleeves, and the cylinder head 17 and its inwardly extending central portion 19 are of the same construction and are indicated by the same reference characters as in Figs. 1 to 5 inclusive. Each of the cylinder walls is provided with a port 53^a which is connected by a branch pipe 80 to a main motive fluid supply pipe or conduit 81 in communication with a motive fluid tank 60, pipe 81 having therein a valve 61. The head is provided with a port or passage 82 registering with the port 53^a, and with a passage 83 in communication with the interior of the cylinder. The passages 82 and 83 extend longitudinally of the head and are connected to a valve casing 84, the valve casing being screwed directly into the cylinder head at the passage 83, while the connec-

130

tion to the passage 82 is made by means of suitable pipe connections 85. The valve casing 84 is provided with a ground valve 86 which is arranged to connect and close the 5 passages 82 and 83. Each of the valves 86 is preferably provided with an arm 87, which is connected to a shifting rod 63. The valve sleeves are provided with ports 51^a and 52^a which are arranged to register 10 with the ports or passages 53^a and 82 in the cylinder wall and head respectively.

Referring to Fig. 9, the cylinder wall is shown as provided with a port or passage 48^a which is in communication with the exhaust passage 16. The cylinder head is provided with a port or passage 90 registering with the port 48^a, and with a passage 91 in communication with the interior of the cylinder. The passages 90 and 91 extend 20 longitudinally of the cylinder and connect with the valve casing 92, the valve casing being screwed into the cylinder head directly above the passage 91, while the connection between the valve casing and the 25 passage 90 is made by suitable pipe connections 93. The valve casing is provided with a ground three-way valve 94 which is arranged to connect and close the passages 90 and 91. Each of the valves 94 is provided with an arm 95 which may be suitably connected with the single shifting rod extending along the cylinders and similar to that shown at 65, Fig. 5. The valve sleeves are provided with suitable ports 46^a and 30 47^a which are arranged at certain times to register with the ports 48^a and 90, in the cylinder wall and head respectively. The valve casing 92 extends upwardly so as to form a cup 96 and is bored as shown at 97, 35 so that when the three-way valve is moved through 90° from the position shown in Fig. 9, a continuous passage will be formed by the passage 91, the valve, and the passage 97.

45 The operation of the starting arrangement and the compression relief is similar to that shown in the first form. This construction in which the ports are located above the lower edge of the downwardly 50 projecting portion 19 of the cylinder head has, however many advantages over the first construction, shown in Figs. 1 to 5 inclusive.

In the first construction, where the ports 55 are located below the cylinder head, it is found that leakage takes place in view of the fact that the cylinder and valve ports will be exposed to the interior of the cylinder. By means of the construction shown 60 in Figs. 7, 8, and 9, however, the starting and compression ports, both in the cylinder walls and valve sleeves, are located above the lower edge of the downwardly extending portion 19 and above the piston ring 98, 65 and between this piston ring 98 and a series

of other piston rings 99. A tight joint will therefore be formed, preventing leakage. The communication between the passages in the cylinder head is made by means of valves 86 and 92 which can be accurately 70 ground and therefore a close fit can be obtained whereby leakage is prevented. It will thus be seen that all the passages from and to the interior of the cylinder are closed either by packing rings, or by ground joints, 75 and therefore an air and gas tight construction is obtained.

In the construction shown in Figs. 1 to 5 inclusive, the connections are necessarily made in the sides of the cylinder walls, 80 where they are inaccessible, but in the construction shown in Figs. 7, 8, and 9, the manually controlled valves are placed on the cylinder heads and the greater part of the connections in case of the starting mechanism, and all of the connections in case of the compression relief mechanism, are made in the cylinder head and its downwardly extending portion, permitting easy inspection and resulting in cheapness of manufacture. 85 90

The motor may be primed by pouring some gasoline into the cup 96 and moving the three-way valve so as to connect passages 91 and 97. Another advantage of this arrangement is that a wire or rod may be 95 inserted through the passages 91 and 97, when they are placed in communication, so that the position of the piston may be located.

The invention may be used to advantage 100 in connection with multicylinder engines as in this type of engine, since there are a number of impulses during a revolution. In a multicylinder engine the valves act as distributors to distribute the starting fluid to 105 the cylinders in succession.

The motive fluid in the tank may be replenished by an air pump driven from the engine or operated in any other suitable manner; or the valves 61 and 62 in Fig. 5, 110 and 61 and 86 in Fig. 7, may be opened for a short time when the engine is in operation, so that a part of the exploded gases in the cylinders will be compressed in the tank. In the latter case the gases, although inert, 115 are not detrimental to the operation of the motor, since the compressed gases are admitted during the explosion stroke only and are subsequently exhausted, before a fresh combustible is drawn in during the suction 120 stroke. Where a motor is used in motor vehicles, the handles 63 and 64 preferably extend up to the vehicle dash so that they may be readily operated by the driver. The valve 61 is merely used to permanently cut 125 off the connection between the tank 60 and the pipe 58, but ordinarily this valve will be open and the connection between the ports 53 and 53^a and the tank will be controlled by the shifting rod 63.

In the claims the terms "sliding valve" or "sliding valves" are used. These terms are used for the purpose of distinguishing from the usual puppet valves. A sliding valve is here to be taken in its broadest sense, namely, one in which the coöperating surfaces slide upon one another as distinguished from a bodily separation as in the case of puppet valves.

10 It is obvious that various changes may be made in the details of construction without departing from this invention, and it is, therefore, to be understood that this invention is not to be limited to the specific construction shown and described.

Having thus described the invention, what is claimed is:

1. In a hydrocarbon motor, the combination with a cylinder and a piston therefor, of valve mechanism including a sliding valve for the cylinder, a starting port controlled by said valve, and a starting fluid supply connected to said port.

2. In a hydrocarbon motor, the combination with a cylinder and a piston therefor, of valve mechanism including a valve sleeve for the cylinder, a starting fluid supply, and means controlled by said valve sleeve for admitting starting fluid to said cylinder to start the motor.

3. In a hydrocarbon motor, the combination with a cylinder and a piston therefor, of valve mechanism including a valve sleeve surrounding the piston, a starting fluid supply, and means to admit the fluid to said cylinder through said valve sleeve.

4. In a hydrocarbon motor, the combination with a cylinder and a piston therefor, of a plurality of valve sleeves surrounding the piston, a starting fluid supply, and means to admit the fluid to said cylinder through said valve sleeves.

5. In a hydrocarbon motor, the combination with a cylinder having inlet and exhaust ports, and a piston for the cylinder, of valve means including a sleeve for controlling said ports, and means controlled by said sleeve for admitting a starting fluid to the cylinder.

50 6. In a hydrocarbon motor, the combination with a cylinder having inlet and exhaust ports, and a piston for the cylinder, of a plurality of sliding sleeves for controlling said ports, and means controlled by said sleeves for admitting a starting fluid to the cylinder.

7. In a hydrocarbon motor, the combination with a cylinder and a piston therefor, of a starting port for the cylinder, a starting fluid supply connected with said port, and valve mechanism including a movable sleeve for controlling said port.

8. In a hydrocarbon motor, the combination with a cylinder and a piston therefor, of a starting port for the cylinder, a start-

ing fluid supply connected with said port, and a plurality of valve sleeves for controlling said port.

9. In a hydrocarbon motor, the combination with a cylinder having inlet and exhaust ports and a piston working in said cylinder, of sleeve valve mechanism surrounding the piston and controlling said ports, and a starting port connected to a compressed gas supply and means controlled by said valve mechanism to admit compressed gas to the cylinder to start the motor.

10. In a hydrocarbon motor, the combination with a cylinder having inlet and exhaust ports and a piston working in said cylinder, of sleeve valve mechanism surrounding the piston and controlling said ports, and a starting port connected to a compressed gas supply and controlled by said valve mechanism to admit compressed gas to the cylinder during the explosion stroke only.

11. In a hydrocarbon motor, the combination with a cylinder having inlet and exhaust ports and a piston working in said cylinder, of sleeve valve mechanism surrounding the piston and controlling said ports, a starting port connected to a compressed gas supply, and controlled by said valve mechanism to admit compressed gas to the cylinder during the explosion stroke only, and a manually operable valve for controlling the starting port.

12. In a hydrocarbon motor, the combination with the cylinder and a piston therefor, of valve mechanism including a sliding valve for the cylinder, a starting port controlled by said valve, and a second valve in said port between said sliding valve and the interior of the cylinder.

13. In a hydrocarbon motor, the combination with the cylinder and a piston therefor, said cylinder having a passage for starting fluid, of a valve mechanism for the motor including a sliding valve, said sliding valve controlling said passage, and a second valve in said passage between the sliding valve and the interior of the cylinder.

14. In a hydrocarbon motor, the combination with the cylinder and piston therefor, said cylinder having a passage for starting fluid, of a valve mechanism for the motor including a sliding valve, said sliding valve controlling said passage, and a second valve in said passage between the sliding valve and the interior of the cylinder, said second valve when closed being adapted to seal said passage.

15. In a hydrocarbon motor, the combination with a cylinder and a piston therefor, of a head, valve mechanism including a sleeve extending between the cylinder and the head, coöperating ports between the

- cylinder and head controlled by said valve mechanism, and manually controlled means for said ports.
16. In a hydrocarbon motor, the combination with a cylinder having inlet and exhaust ports and a piston for said cylinder, of a head, valve mechanism including a sleeve extending between the cylinder and head, and coöperating auxiliary ports between the cylinder and head controlled by said valve mechanism. 70
17. In a hydrocarbon motor, the combination with a cylinder and a piston therefor, of a cylinder and a piston therefor, of a valve chamber formed by spaced members connected to said cylinder, a valve in said chamber, a passage leading from the cylinder to said chamber and controlled by said valve, and an independently controlled valve in said passage. 80
18. In a hydrocarbon motor, the combination with a cylinder and a piston therefor, of a valve chamber formed by spaced members connected to said cylinder, a valve in said chamber, a passage leading from the cylinder to said chamber and controlled by said valve, and an independently controlled valve located in said passage between the first valve and cylinder. 85
19. In a hydrocarbon motor, the combination with a cylinder and a piston therefor, of a head forming with said cylinder a valve chamber, valve mechanism including a sleeve in said chamber, a port in said cylinder and head controlled by said sleeve, and an independently controlled valve for said port. 95
20. In a hydrocarbon motor, the combination with a cylinder and a piston therefor, of a head forming with said cylinder a valve chamber, valve mechanism including a sleeve in said chamber, a port in said cylinder and head controlled by said sleeve, and an independently controlled valve on said head for said port. 100
21. In a hydrocarbon motor, the combination with a cylinder and a piston therefor, of a head forming with said cylinder a valve chamber, valve mechanism including a sleeve in said chamber, a passage in said cylinder and head controlled by said sleeve, and an independently controlled valve in said passage between said sleeve and cylinder. 105
22. In a hydrocarbon motor, the combination with a cylinder and a piston therefor, of a head forming with said cylinder a valve chamber, valve mechanism including a sleeve in said chamber, a passage in said cylinder and head controlled by said sleeve, and an independently controlled valve in said passage between said sleeve and cylinder, and located on said head. 110
23. In a hydrocarbon motor, the combination with a cylinder and a piston therefor, of a head forming with said cylinder a valve chamber, valve mechanism including a sleeve in said chamber, coöperating ports in said cylinder and head controlled by said valve, an independently controlled valve on said head, and passages in said head leading from the port in said head to said valve and from said valve to said cylinder. 125
24. In a hydrocarbon motor, the combination with a cylinder and a piston therein, of a head extending into said cylinder and forming therewith an annular valve chamber, valve mechanism including a sleeve in said chamber, a port in said cylinder and head controlled by said sleeve, and an independently controlled valve for said port. 130
25. In a hydrocarbon motor, the combination with a cylinder and a piston therein, of a head extending into said cylinder and forming therewith an annular valve chamber, valve mechanism including a sleeve in said chamber, inlet and exhaust ports controlled by said sleeve, a port in said cylinder and head controlled by said sleeve, and an independently controlled valve for said port. 135
26. In a hydrocarbon motor, the combination with a cylinder and a piston therefor, of a head forming with said cylinder a valve chamber, valve mechanism including a sleeve in said chamber, and a starting port in said cylinder and head controlled by said sleeve. 140
27. In a hydrocarbon motor, the combination with a cylinder and a piston therefor, of a head forming with said cylinder a valve chamber, valve mechanism including a sleeve in said chamber, and a compression relief port in said cylinder and head controlled by said sleeve. 145
28. In a hydrocarbon motor, the combination with a cylinder and a piston therefor, of a head for said cylinder, valve mechanism including a valve sleeve, a compression relief passage extending through said head, and a valve in said passage and located on said head. 150
29. In a hydrocarbon motor, the combination with a cylinder and a piston therefor, of a head for said cylinder, valve mechanism including a valve sleeve, a compression relief passage extending through said head, and a valve in said passage and located on said head, said valve and passage being constructed to form a straight unobstructed passage when the valve is in a predetermined position. 155
30. In a hydrocarbon motor, the combination with a cylinder and a piston therefor, of a head forming with said cylinder a valve chamber, valve mechanism including a sleeve in said chamber, passages in said cylinder and head controlled by said sleeve including a passage extending longitudinally of the head into the cylinder. 160

31. In a hydrocarbon motor, the combination with a cylinder and a piston therefor, of a head forming with said cylinder a valve chamber, valve mechanism including a sleeve 5 in said chamber, passages in said cylinder and head controlled by said sleeve, a valve on said head and controlling said passage, and a passage extending from the valve and longitudinally of the head into the cylinder.
- 10 32. In a multicylinder hydrocarbon motor, the combination with a plurality of cylinders, pistons therefor and sliding valves for controlling the normal operations of the motor, of a starting fluid supply conduit, 15 and means connected with said valves for distributing the fluid from said conduit to said cylinders.
- 20 33. In a multicylinder hydrocarbon motor, the combination with a plurality of cylinders, pistons therefor, and valve sleeves for controlling the normal operations of the motor, of a starting fluid supply conduit, and means connected with said sleeves for distributing the fluid from said conduit to 25 said cylinders.
34. In a multicylinder hydrocarbon motor, the combination with a plurality of cylinders, pistons therefor and valves for controlling the normal operations of the motor, starting ports for said cylinders, a starting fluid supply conduit connected to said ports, and sliding valves for controlling said ports and distributing the starting fluid to said cylinders.
35. In a multicylinder hydrocarbon motor, the combination with a plurality of cylinders, pistons therefor and valve sleeves for controlling the normal operations of said motor, starting ports controlled by said sleeves, and a starting fluid supply conduit 30 connected to said ports.
36. In a multicylinder hydrocarbon motor, the combination with a plurality of cylinders, pistons therefor and valve sleeves for controlling the normal operations of said motor, starting ports controlled by said sleeves, a starting fluid supply conduit connected to said ports, and independently controlled valve means between said conduit and ports.

In testimony whereof I affix my signature in presence of two witnesses.
